DESIGN FOR A BREASTPIN OR THE LIKE

Elizabeth Parks, Los Angeles, Calif.

Application August 27, 1940, Serial No. 24,643

Term of patent 3½ years

To all whom it may concern:

Be it known that I, Elizabeth Parks, a citizen of the United States, residing at Los Angeles, in the county of Los Angeles, State of California, have invented a new, original, and ornamental Design for Breastpins or the like, of which the following is a specification, reference being had to the accompanying drawing, forming part thereof.

The figure is a front elevational view slightly in perspective, of a breastpin or the like, showing my design.

I claim:

The ornamental design for a breastpin or the like, as shown.

ELIZABETH PARKS.
